UNITED STATES PATENT OFFICE.

JAMES M. GIBERSON, OF ELSAH, ILLINOIS.

RAILWAY-TIE.

SPECIFICATION forming part of Letters Patent No. 378,133, dated February 21, 1888.

Application filed December 15, 1887. Serial No. 258,020. (No model.)

To all whom it may concern:

Be it known that I, JAMES M. GIBERSON, of Elsah, in the county of Jersey and State of Illinois, have invented a new and Improved 5 Railway-Tie; and I do hereby declare that the following is a full and exact description of the same, reference being had to the accompanying drawings, and to the letters of reference marked thereon.

10 My invention relates to an improvement in railway-ties, the object of the same being to provide a metallic tie of more simple construction, and consequently less expensive, than those of the same class heretofore in use, and 15 yet possessing all the requisites to insure the maximum of durability and security.

With this end in view my invention consists in certain details of construction and combination of parts, fully explained in the following specification, and illustrated in the accompanying drawings, in which—

20 Figure 1 is a side elevation of my device, and Fig. 2 is a plan view of the same, both figures being shown in connection with a section 25 of the rails.

25 A represents the tie-bar or tie-plate, consisting of a thin broad plate, preferably a rail-plate, secured at each end by bolts *d*, as shown, to the upper surface of a block of stone or any other 30 equally-durable material. On each side of the part of the tie-plate where the rail *C* rests a rectangular strip of the said tie-plate is cut on two sides only, and then turned up, as shown at *r r*, Fig. 1, so as to form two ears on each side 35 of each end of the tie-bar *A*, said ears and the tie-bar being thus all of one piece, secured to the foundation-blocks *B*, as already explained and shown in both figures of the drawings. Matters being thus and the foundation-blocks

40 set in the ground or upon the road-bed at the required distance apart, the rails are placed within the ears *r*, as shown on the left in Fig. 1, and the latter are then turned down upon the base-flange of the rail, as shown at *r' r'* on 45 the right of the same figure. This being done, the alignment and leveling of the rails are effected by the usual process of tamping.

It is obvious that numerous changes in the form of the parts and minor details of the construction of my tie might be resorted to without departing from the spirit of my invention, and hence I would have it understood that I do not limit myself to the exact form of parts shown and described, but consider myself at liberty to make such changes as come within 55 the scope of my invention.

Having fully described my device, what I claim as new, and desire to secure by Letters Patent, is—

50 A railway-tie consisting of a flat bar of metal secured to foundation-blocks, as described, and having ears *r* for securing the rails, said ears being formed of strips cut and partly detached from the sides of the parts of the tie-plates upon which the rails rest, so as to form a chair 65 or seat for the rail, in which the latter is secured by turning the ears *r* down upon the base-flange of the rail, all of said parts constructed, combined, and adapted to operate substantially as and for the purpose set forth. 70

In testimony that I claim the foregoing I have hereunto set my hand this 26th day of October, 1887.

JAMES M. GIBERSON.
